UNITED STATES PATENT OFFICE

JOSEPH R. MAYHEW, OF DECATUR, ILLINOIS, ASSIGNOR TO MUELLER CO., OF DECATUR, ILLINOIS, A CORPORATION OF ILLINOIS

DESIGN FOR A DRINKING FOUNTAIN

Application filed August 28, 1929. Serial No. 32,566. Term of patent 7 years.

To all whom it may concern:

Be it known that I, JOSEPH R. MAYHEW, a citizen of the United States, residing at Decatur, county of Macon, State of Illinois, have invented a new, original, and ornamental Design for Drinking Fountain, of which the following is a specification, reference being had to the accompanying drawing, forming a part thereof.

Fig. 1 is a top plan view showing my new design,

Fig. 2 is a side elevation, and

Fig. 3 is an end elevation.

I claim:

The ornamental design for a drinking fountain substantially as shown.

JOSEPH R. MAYHEW.
